US00D504407S

(12) **United States Design Patent** (10) Patent No.: **US D504,407 S**
Cohen et al. (45) Date of Patent: **** Apr. 26, 2005**

(54) **MINIATURE RADIO FREQUENCY TRANSMITTER**

(75) Inventors: **Art Cohen**, Cupertino, CA (US); **Julian Peck**, San Francisco, CA (US); **Fadhl Bey**, San Francisco, CA (US); **Dave Noppenberger**, Baltimore, MD (US); **John Glissman**, Valley Ford, CA (US); **Kelly R. Kodama**, Alamo, CA (US)

(73) Assignee: **Aerielle, Inc.**, Mountain View, CA (US)

(**) Term: **14 Years**

(21) Appl. No.: **29/194,380**

(22) Filed: **Nov. 20, 2003**

(51) LOC (7) Cl. **14-03**

(52) U.S. Cl. **D14/155**; D13/168; D13/144

(57) **CLAIM**

The ornamental design for a miniature radio frequency transmitter, as shown and described.

DESCRIPTION

FIG. 1 is an upper left side perspective view;

FIG. 2 is a lower right side perspective view;

FIG. 3 is a right side elevation view;

FIG. 4 is a left side elevation view;

FIG. 5 is a top plan view;

FIG. 6 is a bottom plan view;

FIG. 7 is a front elevation view; and,

FIG. 8 is a back elevation view.
